CUTTER VALVE FOR RELEASE OF FLUIDS

Daniel Mapes, Mamaroneck, N. Y., assignor to
 Walter Kidde & Company, Inc., New York,
 N. Y., a Corporation of New York

Application May 15, 1928. Serial No. 278,009

6 Claims. (Cl. 169—11)

This invention has been developed with particular reference to the release of carbon dioxide under pressure for the purpose of extinguishing fire, but, as will be understood, is capable of application for other purposes and wherever there is interposed between the fluid under pressure and the delivery passage a sealing disc which, so long as it is intact, prevents the loss of the fluid, but which must be ruptured when the fluid is required for use. In Letters Patent of the United States No. 1,674,427, dated June 19, 1928, issued upon the application of Walter H. Freygang, Serial No. 42,710, filed July 10, 1925, and co-pending with the present application, there is shown and described a cutter valve designed for the general purpose above described and in which a device by which the sealing disc is to be ruptured is advanced by hand operated means. When there is but one container the contents of which is to be released it is practicable to operate the cutter valve by hand, but in many cases there must be provided a battery of fluid containers, from all of which the fluid must be released simultaneously in order that the fluid shall be discharged in sufficient volume to meet the conditions. It has been found in practice that the operation by hand of a plurality of such cutter valves is not always practicable and it is therefore the object of this invention to provide means whereby a plurality of such cutter valves can be operated by means other than hand operated devices and preferably by pressure of the fluid which is to be discharged, the operating fluid pressure being derived, through suitable connections, from one of the containers, such, for example, as one of the commercial containers of carbon dioxide liquefied under pressure.

In accordance with the invention the device by which the sealing disc is to be ruptured is carried by a piston behind which may be admitted the fluid pressure necessary to operate the rupturing device. It will be understood that in the extinguishing of fires by carbon dioxide supplied from the ordinary containers in which the fluid is liquefied under high pressure, the pressure of the fluid of a single container is sufficient to operate simultaneously and instantly the cutter valves of a large number of containers.

The invention will be more fully explained hereinafter with reference to the accompanying drawing the single figure of which shows in vertical section a convenient embodiment of the invention, a portion of a single container, with its sealing disc, being also shown.

55 In the drawing—

There is represented at *a* a portion of an ordinary container of carbon dioxide, from which the fluid is discharged through a pipe *b* which is extended nearly to the bottom of the container. To the container is secured one member *c* of a suitable coupling, into which the pipe *b* may be threaded, such coupling member being provided at *c*¹ with a seat for a sealing disc *d*, held in place by a thimble *d*¹. The function of the disc, as is understood, is to prevent loss of the fluid contents of the container. It has in itself sufficient strength to resist the pressure of the fluid. For convenience in manufacture and assembling a second coupling member *e* is formed separately from the coupling member *c* and may be secured thereto by a sleeve nut *e*¹. The coupling member is chambered, as at *e*², to receive with a close working fit, as at *e*³, and at *e*⁴, a piston member *f* which in the construction shown has a passage therethrough to permit the passage of the fluid from the container to the outlet and is formed with a sleeve extension *f*¹ also received with a close working fit in the coupling member, whereby there is provided a means to prevent the passage of gas from the container to the underside of the piston, where it might interfere with the proper operative movement of the piston and the disc rupturing device carried thereby as herein-after described. It may also be formed, as at *e*⁵, with a vent or vents to prevent the building up of back pressure under the piston or as a means to prevent effective resistance to the operative movement of the piston. A spring *g* may be provided between the coupling member *e* and the piston *f* to hold the piston normally in its upper position. A third member *h* of the coupling, also for convenience formed separately, is threaded on the coupling member *e* and is chambered above the piston, as at *h*¹, and is provided with a delivery connection, as at *h*², through which fluid under pressure may be introduced from a suitable source for the operation of the piston and through which, when the sealing disc *d* is ruptured, the contents of the container *a* may pass for delivery at the point required. In the construction shown the piston *f* is extended somewhat above the head of the piston, as at *f*², and is provided with one or more ports, as at *f*³, to establish communication between the container and the delivery passage. Carried by the piston *f* is a device *i* by which the sealing disc *d* is to be ruptured. In the construction shown this rupturing device is a tubular cutter formed with ports *i*¹ which register with ports *f*³ of the piston extension *f*², the construction being such, as ex-

plained in the Patent No. 1,674,427 above mentioned, that forward movement of the cutter with the piston will cut out the central portion of the sealing disc *d* which will then be driven, by the pressure of the fluid contents of the container *a*, through the tubular cutter *i* to a point beyond the ports *i* whereby free communication is established between the container and the delivery passage and the fluid contents of the container find free escape.

Not only is the fire extinguishing fluid available for the operation of the means for effecting the release of the fluid from a battery of containers, so that it is unnecessary to provide other means for bringing about the release of the fluid, such as electrically operated devices, but such fluid pressure operated devices are thoroughly dependable. However, it has been necessary to design the fluid releasing means so as to avoid the possibility of the release of the fluid from one container in advance of the release of fluid from another or others of the containers and the subsequent building up of a pressure in the delivery system which would prevent the operation of the fluid releasing means of other containers and therefore defeat the intention to effect the release at one time of a large volume of the fluid from all of the containers. The fluid releasing means described herein have been designed so as to avoid such a result. It will be seen that in the described construction the fluid which effects the operation of the releasing device is, in the preferred arrangement, admitted through the delivery connection *h*², through which the fluid released from the container also escapes so that there can be no building up of pressure which would tend to prevent the operation of the releasing devices. Furthermore, regardless of the manner in which the released fluid escapes the area of the piston *f* which is exposed to the pressure of the actuating fluid is much greater than the bore of the passage at *e*⁴, through which bore the sleeve extension below the piston or, it might be, the tubular cutter itself, has a close working fit. Furthermore, the chamber *e*² below the piston is vented through the pressure relief openings *e*⁵. Therefore pressure cannot be built up in opposition to the operative movement of the piston and disc rupturing device and the operation of the fluid releasing devices cannot be delayed.

It will be understood that various changes in details of construction can be made to suit different conditions of use and that, except as pointed out in the accompanying claims, the invention is not limited to the particular construction shown and described herein.

I claim as my invention:

1. The combination of a container, a delivery connection, a chambered coupling in communication with the container and the delivery connection, a sealing disc interposed between the container and the delivery connection, a piston mounted in the chamber of the coupling and subject to pressure from an external source and having a sleeve extension above its head provided with a port for communication with the chamber, means to prevent effective resistance to the operative movement of the piston, and a tubular cutter carried by the piston and having a port in registration with the port in the piston extension and adapted to cut out the central portion of the disc in its forward movement with the piston.

2. The combination of a container, a coupling

member secured to the container and formed with a seat, a sealing disc, means to retain the sealing disc on said seat, a second coupling member formed with a chamber, a third coupling member secured to the second coupling member and formed with a delivery connection, a piston mounted in the chamber of the second member, means to prevent effective resistance to the operative movement of the piston, and a tubular cutter carried by the piston and adapted to cut out the central portion of the disc in its forward movement with the piston, the tubular cutter having near its remote end from the disc a port to establish communication between the container and the delivery connection.

3. The combination of a container, a fluid flow connection, a chambered coupling in communication with the container and the fluid flow connection, said coupling member being provided with two chambers connected by a bore of lesser passage dimension than the chambers, said bore constituting the sole direct communication between said chambers, a sealing disc interposed between the container and the fluid flow connection and arranged in one chamber of the coupling, a piston mounted in the second chamber of the coupling and subject to pressure from an external source and having a sleeve extension below its head with a close working substantially gas tight fit within the bore connecting the two chambers, means to prevent effective resistance to the operative movement of the piston, and a device carried by the piston and adapted to rupture the disc in its forward movement with the piston.

4. The combination of a container, a coupling member secured to the container and formed with a seat, a sealing disc, means to retain the sealing disc on said seat, a second coupling member detachably secured to the first coupling member and formed with a chamber and having a fluid flow connection, said last named coupling member having a bore of lesser passage dimension than said chamber, said bore being the sole means of direct communication between said chamber and said sealing disc, a piston mounted in said chamber and subject to pressure from an external source, means cooperating by a close working substantially gas tight fit within said bore to close off communication between the underneath side of said piston and said sealing disc, means to prevent effective resistance to the operative movement of the piston, and a device carried by the piston and adapted to rupture the disc in its forward movement with the piston.

5. The combination of a container, a coupling member secured to the container and formed with a seat, a sealing disc, means to retain the sealing disc on said seat, a second coupling member detachably secured to the first coupling member and formed with a chamber and having a fluid flow connection, said last named coupling member having a bore of lesser passage dimension than said chamber, said bore being the sole means of direct communication between said chamber and said sealing disc, a piston mounted in said chamber and subject to pressure from an external source, means cooperating by a close working substantially gas tight fit within said bore to close off communication between the underneath side of said piston and said sealing disc, said means constituting an integral sleeve extension below the head of the piston, means to prevent effective resistance to the operative movement of the piston, and a device carried by the piston and

adapted to rupture the disc in its forward movement with the piston.

6. The combination of a container, a coupling member secured to the container and formed with 5 a seat, a sealing disc, means to retain the sealing disc on said seat, a second coupling member detachably secured to the first coupling member and formed with a chamber and having a fluid flow connection, said last named coupling member 10 having a bore of lesser passage dimension than said chamber, said bore being the sole means of direct communication between said chamber and said sealing disc, fluid operated means mount- ed in said chamber and subject to pressure from an external source, means cooperating by a close working substantially gas tight fit within said bore to close off communication between the underneath side of said fluid operated means and said sealing disc, means to prevent effective resistance to the operative movement of the fluid operated means, and a device carried by the fluid operated means and adapted to rupture the disc in its forward movement with the fluid operated means. 80 85
